DESIGN FOR A CARPET.

SPECIFICATION forming part of Design No. 13,796, dated March 20, 1883.

Application filed January 25, 1883. Term of patent 3½ years.

To all whom it may concern:

Be it known that I, HENRY HUNT, of Greenville, in the county of Hudson and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The group A is a large flower and leaf group resting upon a bracket-like support. The group

B is a smaller group of open flowers and leaves closely massed at the center. From both groups project flower and blossom sprays and leaves, and the ground is filled in with smaller flower and leaf forms, and with Greek-letter ornamentation, all as shown in the photograph.
